Attorney

G. Wright Arnold.

UNITED STATES PATENT OFFICE.

LOUIS F. WASSON, OF ELLENSBURG, WASHINGTON.

CARBURETOR.

1,408,786.

Specification of Letters Patent. Patented Mar. 7, 1922.

Application filed April 17, 1917. Serial No. 162,596.

To all whom it may concern:

Be it known that I, LOUIS F. WASSON, a citizen of the United States, residing at Ellensburg, in the county of Kittitas and State of Washington, have invented a certain new and useful Improvement in Carburetors, of which the following is a specification.

My invention relates to improvements in carburetors.

The objects of my invention are: to provide a carburetor whereby a sufficient volume of fuel in the form of carbureted air shall be supplied to the cylinders of the engine so that the fuel consumed shall be dependent upon and in direct proportion to the power required without the loss of any of said fuel; to provide a carburetor which shall produce good atomization of the liquid fuel with the throttle wide open as well as when nearly closed and to provide a carburetor which automatically adjusts itself to the necessary conditions to achieve this result.

The above mentioned objects of my invention, together with others inhering in the same, are obtained by the mechanism illustrated in the following drawings, the same being merely a preferred form of embodiment of my invention, throughout which drawings like reference numerals indicate like parts.

Figure 1 is a plan view of one form of carburetor embodying my invention; Fig. 2 is a view of the same in vertical section on broken line 2, 2 of Fig. 1; Fig. 3 is a fragmentary view of the same in vertical section on broken line 3, 3 of Fig. 2; Fig. 4 is a view in horizontal section on broken line 4, 4 of Fig. 2; and Fig. 5 is a view in vertical section on broken line 5, 5 of Fig. 4 of a portion of the same.

The objection to carburetors as heretofore constructed wherein the liquid fuel is discharged into the chamber of air in the form of a spray consists in their failure to finely atomize the fuel when the throttle is opened widely, so that the resulting mixture contains large globules of raw gasoline entering the manifold.

On the inner side of the continuous outer wall 1 of my device is secured in a suitable manner a lining 2 having the function of a wick, and upon the outer side of the inner wall 3, concentric with the wall 1, is secured in a suitable manner a covering 4 having the function of a wick, similar in all respects to

the lining 2. The wall 3 is not continuous, but provides openings 5 and 6 upon the sides of the wall 7 which divides the space enclosed by said wall 3 into two compartments 60 8 and 9, compartment 9 communicating directly with the intake manifold 10. The wall 7 extends to the wall 1. The annular recess between the wick walls 2 and 4 is represented at 11. A little way above the 65 bottom 12 of the annular recess 11 is the fixed floor or partition 13, which construction provides the annular compartment 14, which compartment is supplied with liquid fuel, such as gasoline, by the pipe 15 from 70 a float-valve controlled reservoir.

The chambers formed by the walls 1 and 3 are entirely covered by the plate 16 through which are openings 17 and 18 into the pipe 19 through which pure air enters the carburetor, either at atmospheric temperature or in a heated condition from adjacent heated parts of the engine. The valve 20, operated by the lever 21 secured to the rod 22, permits pure air to pass directly into 80 the compartment 9. The throttle is represented as 23. To remove any liquid fuel which accidentally might get above the floor 13, there is provided a small drain 24.

The operation of my carburetor is as follows: Liquid fuel, such as gasoline, enters the compartment 14 through the pipe 15, said compartment being kept continuously full by a suitable valve. Extending into the liquid fuel are annular linings, such as 90 wicks 2 and 4, which are thus kept in a saturated condition by the liquid rising in them above the fixed floor 13 by a capillary attraction. Air enters through the pipe 19, then passes through the opening 17 into the compartment 8, thence out through the opening 5 into the annular wick lined recess 11, wherein the moving air becomes mixed or charged with the liquid fuel from the saturated wick linings by passing entirely 95 through and around the annular recess or passageway 11; and then the mixture of air and fuel passes through the opening 6 into the compartment 9 from which it flows directly past the open throttle 23 into the intake manifold 10. This construction precludes raw gasoline in the form of globules or otherwise reaching the engine cylinders and provides a carburetor which insures a mixture of air and fuel as the explosive 100 mixture entering the intake manifold and engine cylinders, because the air at no point

comes in contact with the free liquid fuel. Manifestly, as the consumption by the engine of the explosive mixture increases upon opening the throttle it will draw the air 5 through the wick lined annular recess 11 at a faster rate. Opening 5 is larger than opening 6, the one nearest the throttle, so that the air is retarded in the annular passageway or recess 11 sufficiently to insure 10 its being well charged or mixed with the liquid fuel and furthermore, the reducing of the opening 6 as compared with opening 5 is for the purpose of preventing any undue suction in the annular recess 11; that is, 15 so that liquid fuel is not drawn into the said recess. Not only is opening 6 smaller than opening 5 but it is small as compared to the mixture carrying capacity of the recess 11. Such construction insures the recess 11 being 20 at all times filled with air and in this way the said undue suction is eliminated. The contorted course of the air entering the opening 17 assists in thoroughly mixing the liquid fuel and the air to provide a homogeneous mixture. When a lean explosive 25 mixture is desired, air may be admitted directly into compartment 9 by opening the valve 20. The best results are attained when the valve 20 is slightly open so that some 30 air at all times is being admitted to compartment 9. The valve advantageously may be opened widely after the carburetor becomes heated by the operation of the engine, since the rate of absorption from the wicks is 35 increased by the heated condition of the carburetor.

Obviously, changes may be made in the forms, dimensions and arrangements of the parts of my invention, the above only setting forth a preferred form of embodiment 40 of my invention, without departing from the principle or the spirit thereof.

I claim:

1. A carburetor which embodies a liquid fuel compartment, a mixing passage with a wick-like lining operatively communicating with said fuel compartment, a partition separating said fuel compartment from said passage, an opening for the admission of 45 air to said passage to pass along the surface of said wick-like lining and an outlet opening smaller than said admission opening for the direct withdrawal of the charged air from said passage without said air passing 50 through said wick-like lining, said outlet opening being located at the opposite end of the mixing passage.

2. A carburetor which embodies a liquid fuel compartment, an annular mixing passage with a wick-like lining operatively communicating with said fuel compartment, a partition separating said fuel compartment from said passage, a slot for the admission 60 of air to said passage to pass over said 65 wick-like lining and a slot smaller than said

admission slot for the direct withdrawal of air from said passage without passing through said wick-like lining, said last slot being located at the opposite end of the mixing passage, whereby a whirling motion is imparted to the air in its passage through the carburetor. 70

3. A carburetor which embodies a liquid fuel compartment, a narrow passageway with a wick-like lining communicating with 75 said fuel compartment by capillary action, said passageway being provided with an air admission opening practically as long as the said passageway is high for the free entry of air to said passageway, wherein said air 80 becomes charged with fuel, an outlet opening practically as long as the said passageway is high and narrower than said admission opening, the discharging capacity of said outlet being relatively smaller than the 85 capacity of said passageway, whereby interfering engine suction is so eliminated within said passageway that liquid fuel is not drawn into said passageway except by said capillary action, said withdrawal vent permitting the charged air to pass to the engine cylinders. 90

4. A carburetor which embodies a liquid-fuel compartment, a narrow passageway with a wick-like lining communicating with 95 said fuel compartment by capillary action, a partition separating said fuel compartment from said mixing passage, said passageway being provided with an air admission opening for the free entry of air 100 thereto to the full capacity of said passageway, wherein said air becomes charged with fuel by passing along the wick, said passage being further provided with an outlet opening whereby the said air charged with fuel may be directly withdrawn without passing through the wick-like lining, the discharging capacity of said outlet opening being relatively smaller than the capacity 105 of said passageway, whereby interfering engine suction is so eliminated within said passageway that liquid fuel is not drawn into said recess except by said capillary action. 110

5. A carburetor which embodies a liquid fuel compartment, an admission and withdrawal chamber surrounded by a narrow passageway, the walls of which passageway are provided with a wick-like lining, said lining being so disposed with respect to the liquid fuel compartment that it may be kept saturated with said liquid fuel but separated therefrom by a partition, said admission chamber being provided with an opening by which air may pass to said passageway where it 115 becomes charged with fuel absorbed from the said wick-like lining, and said withdrawal chamber being provided with an opening by which said charged air may pass from said passageway to said withdrawal chamber, 120 125 130

said last opening being smaller than said admission chamber opening.

6. A carburetor which embodies a liquid fuel compartment, a mixing passageway 5 with a wick-like lining communicating with said fuel compartment by capillary action, an air admission chamber provided with an opening into said passageway, said opening functioning to admit uncharged air to said 10 passageway to the full capacity of said passageway and a withdrawal chamber provided with an opening into said passageway for the direct withdrawal of the charged air from said passageway without 15 passing through the wick-like lining, both of said chambers, the admission and withdrawal, being surrounded by said passageway, the discharging capacity of said withdrawal opening being relatively smaller than 20 the mixture carrying capacity of said passageway, whereby interfering engine suction

is so eliminated within said passageway that liquid fuel is not drawn into said passageway except by capillary action.

7. A carburetor embodying a mixing passageway formed by two concentric cylindrical wick-lined walls, i. e., an outer and an inner wall, a third wall extending diametrically across said passageway and diametrically through the center of said cylindrical walls to the inner wall, admission and withdrawal compartments bounded by said inner wall, said third wall forming a partition between said compartments, openings in said inner wall forming an admission 30 port to and a withdrawal port from said passageway, and a liquid fuel compartment 35 into which said wicks extend.

In witness whereof, I hereunto subscribe my name, this 9th day of April, A. D. 1917. 40

LOUIS F. WASSON.
